SYLVANIA.

INSULATOR-SUPPORT.

1,212,394.

Specification of Letters Patent. Patented Jan. 16, 1917.

Application filed April 6, 1916. Serial No. 89,365.

To all whom it may concern:

Be it known that I, CHARLES L. PEIRCE, Jr., a citizen of the United States, and a resident of Pittsburgh, in the county of Allegheny and State of Pennsylvania, have invented certain new and useful Improvements in Insulator-Supports, of which the following is a specification.

My invention relates to insulator supports particularly to that class of supports made of cast iron or of sheet metal of comparatively heavy gage and with insulator receiving threads formed directly thereon.

Insulator supports of the above class are very unyielding at the insulator receiving end and the threading is not always true and smooth. Likewise, in insulators which are molded of porcelain or glass the threaded bore is not always of standard size and smooth. There is also considerable difference in the coefficients of expansion of metal and glass or porcelain. Therefore, breakage frequently occurs during application of the insulator to the support or so much stress is put into the insulator during application that slight shocks or jars or unequal expansion or contraction will later on cause cracking or breaking of the insulator. The insulator receiving end of the support could, of course, be made slightly smaller than the insulator bores but then the insulator would not be seated securely enough on the support and would jar loose and rattle or would turn with the slightest pull on the wires supported thereon.

In general the object of my invention is to provide construction and arrangement for overcoming the above referred to defects and to provide a rigid and secure yet yielding support for insulators.

More in detail the invention contemplates the provision of locking mechanism in the form of a lever structure comprising a longitudinal arm and a transverse arm so arranged that an insulator can readily be applied without straining it and that during the final seating movement of the insulator the top of its bore will engage with the transverse arm of the lever structure to shift the longitudinal arm yieldingly and firmly against the insulator side to lock the insulator securely to the support against loosening or displacement.

On the accompanying drawing I have

shown an insulator support embodying the various features of my invention.

On this drawing, Figure 1 is a front elevational view of an insulator supporting bracket, Fig. 2 is a sectional view on plane 2-2, Fig. 1, Fig. 3 is a plan view of the insulator receiving end of the bracket, Fig. 4 is a similar view with the locking mechanism removed, and Fig. 5 is a similar view showing a modified arrangement.

The supporting bracket shown is of U-shape and formed from a single piece of sheet metal, the body part 10 of the bracket being of arch or U-shaped cross-section, and the limbs 11 and 12 being parallel or at an angle with each other. At the outer end of the bracket the limbs 11 and 12 are brought together to form the insulator receiving end *e* of circular cross-section throughout, and this end has the threads 13 formed thereon for fitting the threads of insulators. Any suitable means may be provided for securing the bracket to a support. As shown wings 14 provided with bolt holes 15 extend laterally from the inner end of the bracket.

In the front side of the insulator receiving end *e* is the longitudinal slot 16 and at the upper end of this slot a pivot member 17 extends transversely across the inside of the end *e* a distance to the rear of the slot 16. As shown in Figs. 1, 2 and 3, the slot 16 and pivot member 17 are provided for during formation of the blank for the bracket, that is, the ends of the limbs 11 and 12 are cut out, and these cut-out sections meet to form the slot 16 when the blank is bent and pressed into form. The pivot member 17 is in the form of a tongue cut from the blank and then bent into the position shown when the bracket is formed. The pivot member supports an L-shaped lever structure 18 preferably formed of steel wire. As shown, a length of wire has one or more circular turns 19 for receiving the pivot member 17 and one arm 20 of the wire extends transversely across the top of the insulator receiving end *e* and the other arm 21 of the wire extends downwardly between and parallel with the sides of slot 16. The lever structure is thus pivoted for swing in its plane on the pivot member 17, and when an insulator such as *I* is applied to the threads 13, the top of the insulator bore will eventually engage with and press downwardly

on the transverse arm 20 of the lever, and the longitudinal arm 21 will be forced outwardly against the insulator side and the insulator will be locked against loosening or displacement. The arm 21 may be crimped as shown in accordance with the threads 13 in order to fit the insulator threads. To limit the inward movement of the arm 21 its end 22 may be deflected at right angles 10 into and through the end *e* to abut against the side opposite the slot 16. Preferably the arrangement is such that this end 22 will hold the longitudinal arm 21 a short distance outside of the slot 16 so that this arm 15 will be sprung or deflected inwardly during application of the insulator. The end 23 of the arm 20 may be deflected downwardly into the end *e*, the arm 20 being preferably arched upwardly so as to present 20 a smooth and rounded engaging surface to the top of the insulator when the insulator is turned to final position to exert pressure on the arm 20 to rotate the lever 18 to force the arm 21 outwardly against the insulator side. 25 With the above arrangement the threads 13 can be of slightly smaller diameter than ordinarily in order that the insulator will not be strained by engaging during its application to the more or less unyielding 30 end *e*. During such application and before the insulator is finally seated the lever arm 21 will exert its spring action against the insulator to hold it firmly but yieldingly to the threads 13 and then when the insulator 35 is finally seated the arm 21 will be positively forced more intimately against the insulator threads to then lock the insulator securely in seated position. The insulator can readily be removed when desired, for 40 as soon as it is turned backwardly its pressure against the lever arm 20 will be released and consequently the clamping engagement of the arm 21 against the insulator will be released so that the insulator can then be 45 readily unscrewed.

As there will be considerable strain on the pivot arm 17 I preferably support the free end thereof. As shown in Figs. 1, 2 and 3, the metal at the top of the end *e* is 50 cut away in the blank to leave the seat 24 and shoulder 25 for the end of the tongue 17, the free end of the tongue resting on the seat 24 and against the shoulder 25 to be supported and strengthened against the 55 downward and inward pressure thereon when the insulator is seated against the lever structure 18.

In Fig. 5 I have shown a modified arrangement. Instead of forming the pivot member 17 integral with the bracket a steel pin 26 may be used and supported in the sides of the end *e* behind the slot 16. Also instead of using cylindrical wire for the lever structure as shown in Figs. 1, 2 and 3, wire 27 of rectangular cross-section can be

used; or instead of bending the lever member from wire it could be otherwise formed. Other changes and modifications are also possible which would all come within the scope of the invention and I do not therefore desire to be limited to precisely what I have shown and described. The support of my invention gives a yielding seat at all times to the insulator so that the insulator is never under extraordinary strain and the insulator, after application is locked to the yielding seat against loosening or displacement and can be readily unscrewed when desired.

I claim as follows:

1. In an insulator support, the combination with the insulator receiving end, of a locking lever pivoted on said end with one arm extending transversely thereover and the other arm extending longitudinally 85 downwardly, engagement of the top of an insulator with the transverse arm of the lever causing clamping of the longitudinal lever arm against the insulator side.

2. In an insulator support, the combination with an insulator receiving end, of a clamping member pivoted thereon in the path of the top and sides of an insulator to exert upward and lateral clamping pressure against an insulator when it is applied.

3. In an insulator support, the combination with an insulator receiving end, a pivot member extending transversely across said end, a lever pivoted on said member and having one arm extending transversely 100 across said end and above the top thereof and having another arm extending downwardly adjacent the side of said end, said downwardly extending arm being swung outwardly into clamping engagement with 105 an insulator when the transverse arm is engaged by the insulator top.

4. In an insulator support, the combination with an insulator receiving end of circular cross-section, a pivot member extending transversely across said end at the top thereof, a longitudinally extending slot in said end below said pivot member, and a lever pivoted to said pivot member and having an arm extending transversely and 110 above said end and having another arm extending downwardly adjacent said slot, said lever being free to swing to carry its downwardly extending arm laterally outwardly through said slot when pressure is 115 applied to the transverse arm.

5. In an insulator support, the combination with an insulator receiving end, of an insulator clamping member pivotally supported on said end and having a transverse 125 arm and a longitudinal arm, said end having a slot for normally receiving said longitudinal arm, said transverse arm being in the path of the top of an insulator when applied to said end and when engaged by the 130

top effecting swing of the clamping member to force its longitudinal arm outwardly through the slot and against the insulator side.

- 5 6. In an insulator, the combination with an insulator receiving end having a longitudinal slot in its side, a pivot member extending transversely at the top of said end and slot, an L-shaped lever structure pivoted
10 on said pivot member and having one arm extending transversely across the top of said end in the path of the tops of insulators applied to such end and having an arm extending downwardly and normally within said
15 slot to be shifted outwardly into clamping engagement with the insulator side when the insulator top is brought against the transverse arm.
7. In an insulator support, the combination with an insulator receiving end, an L-shaped lever structure pivoted at its bend at the top of said end and having an arm extending across the top to be in the path of the tops of insulators applied to the end, said lever structure having an arm extending downwardly to be brought into clamping engagement with the insulator side when
20
25

said lever is swung by the engagement of the insulator top with the transverse arm of the lever.

8. An insulator support comprising a body part formed from a single piece of sheet metal with its end of circular cross-section to form an insulator seat, said end having a longitudinal slot, a pivot member 30 extending across said end at the top of said slot, a lever structure of spring material pivoted on said pivot member to swing in a vertical plane and having an arm extending transversely with the top of said end 40 and having an arm extending downwardly in register with said slot, said transverse arm being engaged by an insulator top during final seating of an insulator on said end and said lever being swung during such 45 engagement to force its longitudinal arm outwardly through said slot and against the insulator side to clamp the insulator to the end.

In witness whereof I hereunto subscribe 50 my name this 26th day of February, A. D., 1916.

CHARLES L. PEIRCE, Jr.
